AUTOMATIC RECORDING AND REPRODUCING DEVICE

Jesse J. Warner, San Francisco, Calif.

Application June 26, 1939, Serial No. 231,209

16 Claims. (Cl. 179—100.4)

My invention relates to automatic recording and reproducing units and more particularly to a fully automatic device which will make a record, play it back and deliver it to a customer.

5 Among the objects of my invention are: to provide a completely automatic recording and reproducing unit; to provide such a unit adaptable for coin operation; to provide such a unit as will record a speaker's voice, automatically give a playback, thereafter deliver the record to the speaker, and repeat the cycle of operation as required.

10 Other objects of my invention will be apparent or will be specifically pointed out in the description forming a part of this specification, but I do not limit myself to the embodiment of the invention herein described, as various forms may be adopted within the scope of the claims.

In the drawings,

15 Figure 1 is a perspective view of a complete automatic recorder and reproducer unit as installed in a cabinet.

20 Figure 2, is a top plan view of the operating mechanism of one preferred form of my invention.

25 Figure 3 is a rear plan view showing the main operating shaft taken as indicated by the line 3—3 in Figure 2.

Figure 4 is a view partly in section and partly 30 in elevation taken as indicated by the line 4—4 in Figure 2.

Figure 5 is a view partly in section and partly 35 in elevation taken as indicated by the line 5—5 in Figure 2.

Figure 6 is a view partly in section and partly 40 in elevation taken as indicated by the line 6—6 in Figure 3.

Figure 7 is a view partly in section and partly 45 in elevation taken as indicated by the line 7—7 in Figure 3.

Figure 8 is a view partly in section and partly 50 in elevation taken as indicated by the line 8—8 in Figure 3.

Figure 9 is a view partly in section and partly 55 in elevation taken as indicated by the line 9—9 in Figure 3.

Figure 10 is a view partly in section and partly 60 in elevation taken as indicated by the line 10—10 in Figure 3.

Figure 11 is a view partly in section and partly 65 in elevation taken as indicated by the line 11—11 in Figure 3.

Figure 12 is a view partly in section and partly 70 in elevation showing the visual indicator of record playing and recording time.

Figure 13 is a schematic circuit diagram showing the connections for the various elements illustrated in the preceding figures.

Referring directly to Figure 1 for the general appearance of the device of my invention, a cabinet 12 is divided by partition 14 into two portions, a front recording chamber 16, and a rear apparatus chamber 18. The upper portion of partition 14 is preferably a glass panel 20. Recording chamber 16 is provided with a door 22, and partition 14 is provided with a record delivery chute exit 24, and a coin slot 26. Glass panel 20 has set therein a transducer 28, acting as a microphone to record, and as a loud speaker to reproduce, the voice.

The general sequence of operation of my invention is: (1) The setting of the device into action by the insertion of a coin. (2) The placing of a record on the turntable. (3) The cutting of the record. (4) The playback of the record, and (5) the delivery of the record to the speaker or customer. I will describe in detail one preferred form of the invention, a general layout of which, and the relationship of the parts, is shown in Figures 2 and 3. The remainder of the figures are detailed views of various portions of the apparatus and will be referred to more specifically from time to time.

Referring first, therefore, to Figures 2 and 3, a mounting panel 40 is provided with a bracket 30 42 on which is mounted a motor 44 having a vertical shaft. Motor 44 through a friction wheel 46 drives a countershaft 47, this countershaft being provided with a belt pulley 48 driving turntable 50 by means of belt 52. Turntable 50 is provided with the usual centering pin 53, as shown in Figures 2 and 5. Countershaft 47 is also provided with pinion 54 driving a larger spur-gear 56 mounted on a vertical cutting head driveshaft 58. This recording head driveshaft extends upwardly through panel 40 and by means of worm-gears 60 rotates a horizontal cutting head driveshaft 62 as shown in Figure 10. A cutting head 64 is mounted on a pivoted arm 66, one portion 68 of which extends below panel 40 and terminates in a cam follower 70 as shown in Figure 5. Arm 66 is hinged to a driven bracket 72 and the vertical motion of cutting head 64 without raising bracket 72 is limited by a cutting head adjustment screw 74. Driving bracket 72 is driven by having attached thereto half nuts 76 meshing with driving threads 78 on horizontal cutting head driveshaft 62.

Also attached to cutting head driven bracket 72 is a driven link 80 extending beyond the ex-

tent of the driving threads 78 as shown in Figure 12. Link 80 operates a pointer 82 over face 84, showing the position of the cutting head 64 with relation to the record being cut. Each end 5 of the travel path of the cutting head 64 is indicated by pilot lamps 86 and 88 later to be described.

I will now describe the mechanism mounted on cam shaft 92 in order, starting from worm 10 gears 90. First, record feed gear 94 drives a record feeding shaft 96 by meshing with a second record feed gear 98 mounted on shaft 96. Inasmuch as I may desire to disconnect these gears, for reasons to be described later, I have mounted, 15 as shown in detail in Figure 6, record feeding shaft 96 on a hinged arm 100 and then have provided a lever 102 rotating on shaft 96 and having a notch 104 on one end therefore, this notch fitting cam shaft 92. The distance between notch 104, however, and the axis of shaft 96 is such so that when notch 104 is placed around shaft 92, gears 94 and 98 are disconnected. The angular displacement is provided for by making bearing 105 at the other end of shaft 96 to 25 have a loose fit.

On this other end of shaft 96, I position a feed worm gear 106 driving a secondary record feed shaft 108, and shaft 96 terminates in a crank 110, so that when record feed gears 94 and 98 are disconnected, secondary shaft 108 can be 30 turned by hand.

The details of the record feeding mechanism are shown more clearly in Figure 4. Here the secondary record feeding shaft 108 drives a vertical rack 112 by means of pinion gear 114. Rack 35 112 is attached to vertical pillar 116 extending upwardly through panel 40 in pillar bearing 118. Pillar 116 supports, at top and bottom, two parallel vertical record carrying bars 120 each provided with notches 122 into which record discs 124 fit, stacked one above another as shown in Figure 4. Although it is obvious that the system herein described is applicable to handle any type of disc record, I prefer to use thin aluminum 40 discs. Parallel bars 120 are spaced apart less than the diameter of the records, and the records are held in notches 122 by spring bar frame 126 forced against the projecting edges of each record by spring 128. It will thus be seen that disconnection of gears 94 and 98 is for the purpose of allowing manual rotation of secondary feed shaft 108 with crank 110, to raise the record carrier to its highest position to enable loading 45 of records therein.

Immediately beneath the stacked records is a horizontal slide 130 movable across panel 40, and having two upwardly projecting ribs 132. These ribs carry, adjacent pillar 116, upwardly projecting lugs 134 positioned to catch the pillar 50 side of a single record on the bottom of the stack. Slide 130 is moved toward turntable 50 by the action of segmented gear 136 mounted on cam shaft 92. The details of the slide drive are shown 55 in Figure 11 taken in conjunction with Figure 2. During a portion of the revolution segmented gear 136 a slide pinion 138 is engaged, to which is attached a cable arm 140 pulling a cable 142 over rollers 144 and 145. Cable 142 is secured to slide 130 at the pillar end thereof. Slide pinion 138 makes one complete revolution during the contact with the toothed portion of the segmented gear 136 and the slide, during that revolution, is driven toward the turntable, but is retracted 65 therefrom by weight 146 attached to the other

end of cable 142 after the cable has passed over weight pulley 145.

On panel 40, running parallel to slide 130, and adjacent thereto on both sides thereof, are raised record support ribs 147 as shown in Figures 4 5 and 5, on which the bottom record may travel. To keep the records in line with the turntable, lateral record guides 148 are also provided. The turntable ends of ribs 147 terminate just short of the turntable aperture with angular bevels 149 to 10 direct the moving record on to panel 40 just over turntable 50. The record will rest there until picked up by the rising of the turntable, as the turntable aperture is smaller than the record. On the opposite side of turntable 50 is a delivery 15 slot 51 cut through panel 40 of record diameter length.

Next to segmented gear 136 on cam shaft 92, is a turntable raising cam 150. Spaced a bit further on the shaft 92 is a cutter head lifting and 20 returning cam 152. These two cams and their cooperation with the cutter head and turntable are shown more in detail in Figure 5. The turntable axle 154 slides in a turntable bearing 156 mounted on a turntable bracket 158, the turntable being rotated by belt 52 engaging turntable pulley 160. Turntable axle 154 is, however, free to slide vertically in bearing 156, and is controlled by turntable raising arm 162 bearing against pointed end 164 of the turntable axle, and pivoted 25 on stationary arm bracket 166. The end of arm 162 terminates in a cam follower 168, thus we have side by side, two cam followers, cam follower 168, previously described as being attached to arm 68 carrying cutter head 64 and cam follower 168 controlling the raising and lowering of turntable 50. Cam follower 168 rides on turntable cam 150 and cam follower 70 rides against the spiral lifting and returning cam 152.

The next mechanism positioned on shaft 92 40 is a pair of bevel gears 170 rotating shaft 172, this shaft terminating in reproducer arm cam 174. Cam 174 is semi-cylindrical and bears against reproducer arm cam follower 176 attached to reproducer arm 178 swingable across 45 turntable 50 on reproducer arm pivot 179. Cam 174 is provided with a square leading edge 180 and a forked trailing edge 181. This fork centers follower 176 so that arm 182 will always be lowered on to a record on turntable 50 at the beginning of the cut track, and the square leading edge lifts the reproducer arm off the record after the playback is finished. No attempt is made to definitely position the reproducer arm during the time it is off the record as fork 181 will always start the playback at the right position. Cam follower 176 extends through panel 40 in an arcuate aperture 183, the limits of which determine the amount of lateral swing arm 182 may take, and this limited swing is held to be just 50 over the limits of the cut surface on the record, and to keep follower 176 always on the surface of cam 174 when lifted.

Also, on shaft 92, beyond bevel gears 170, first 65 is positioned a switch cam 184 operating a switch 186 as shown in Figure 7 which controls the shifting of an amplifier circuit, to be described later, from cutting connection to reproducing connection.

Next comes pilot switch cam 190 which controls 70 pilot switch 192 as shown in Figures 9 and 13 which controls the energization of signal lamps 86 and 88, indicating the start and stop of recording time.

At very end of shaft 92 is positioned a freely 75

rotating arm 194, having projecting laterally therefrom, an arm pin 196. The details of this construction are shown in Figure 8. Arm 194 is provided with a terminal weight 198 and shaft 92 5 is provided with a rotating pin 200 engaging pin 196 to raise arm 194 to the vertical position. After the arm 194 passes the upper vertical position it will fall, through the influence of weight 198 on the end thereof, and in falling contacts 10 the end of trip 202, locked back of trip bracket 204 and held in that position by trip spring 206. Trip 202 is attached to main switch arm 208 15 operating main switch 210, and trip 202 is reset by pin 212 attached to coin slot 26, the details of which are not shown because such switches are well known in the art and are no part of the present invention.

Referring to Figure 13 for the electrical connections of my invention, A. C. mains 220 are 20 connected through fuse 222 to cabinet lights 224 and to motor 44 through main switch 210. A. C. is also led directly to amplifier 226 which has output leads 228, a phonograph input lead 230 and a microphone input lead 232. In the microphone 25 input lead 232, is positioned an input transformer 234, and switch 186 connects the reproducer 182 to the microphone input, and the transducer 28 to output circuit 228, thus placing the device in position to play back a record when cam 184 30 bears against switch 186. When, however, cam 184 passes off switch 186, transducer 28 is connected to input transformer 234 and the cutting head 64 operates in output circuit 228, under the influence of the voice of the customer to cut a 35 record. At the same time, switch 192 is determined by position of cam 190, lights green lamp 86 at the start of the record, and red lamp 88 at the end of the record to indicate to the customer his recording time. Intermediate these two 40 conditions pointer 82 shows the relative length of time left for recording.

Having described the mechanical and electrical assembly of my invention, I will now describe the sequence of operation. It will be assumed that 45 a record is in position on panel 40 above turntable 50 and that cutting head 64 is positioned over a peripheral area of the record at which cutting is to start, but not in contact with the record, and that slide 130 has not been withdrawn. At this point, the mechanism has been 50 stopped by the action of swinging arm 194 tripping off main switch 210 after purveying a previous record. If then, a coin is inserted in coin 55 slide 26 and the slide pushed forward, main switch 210 is operated and the trip 202 is locked behind trip bracket 204. The main switch 210 energizes motor 44 and amplifier 226; and switch 186 has connected the transducer 28 to the cutting 60 head 64. Withdrawal of the slide begins and at the same time pillar 116 starts its downward movement. When the slide 132 reaches the end of the stroke the segmental gear 136 disengages and leaves the slide stationary but the record carriage continues to move downwardly and does 65 so during the entire sequence of operation. At the end of the cycle of operation when the segmental gear 136 again encounters pinion 138 to move the slide, the lowest record is in position to be picked up by slide lugs 134. In the meantime, 70 the turntable is being rotated at cutting speed and is being raised by the action of cam 150 on cam follower 168 to pick up the record and rotate it with the turntable. The time elapsed from the start of the motor until the record starts to 75 be cut, allows the amplifying apparatus to warm

up to amplifying condition. Cutting head 64 is lowered and half nuts 76 engage threads 78 before the cutting head reaches the record. Thus the head 64 is in lateral motion before cutting starts, thereby preventing a closed circular cut on the 5 first cutting revolution. At the same time switch 192 has energized the green lamp 86 to indicate the start of the recording time. The customer then makes his recording, meanwhile watching pointer 82 as it moves across the chart 84 and 10 keeps on talking until the red lamp is energized, due to the cam 190 disengaging switch 192. At this point, switch 184 also disconnects and switch 186 returns to its other position energizing reproducer 182 and connecting transducer 28 as a 15 loud speaker.

In the meantime, cam 174 allows reproducer 82 to contact the record at the start of the cut track and the playback commences. Before playback, cutting head 64 has been raised and disconnected from driving threads 78 and is being returned to peripheral starting position again by action of spiral lifting and returning cam 152 against cam follower 70.

After the playback is finished, cam 174 lifts 25 the reproducer 182 off the record. Segmental gear 136 starts motion of slide 130 toward the turntable and the turntable lowers, releasing the record. The cut record, being lower than the turntable ends of slide 130 is pushed laterally by 30 these ends, as the turntable drops, into slot 51 in panel 40 to be delivered by a chute not shown, to chute exit 24, for delivery to the customer.

As the motion of the slide 130 toward the turntable continues it carries the lowest record in 35 the record stack until this record drops over bevels 149 and slides into position over the turntable 50. In this position the main switch is tripped by weight 198 as previously described and the device stops ready for the next cycle of operation. 40

It will be seen that the record carrier continues to proceed downwardly with every record delivered. It is to be recharged with new records whenever coins are removed from the cabinet 45 by periodical visits of an inspector. This recharging is accomplished by the manual return of the record carriage to high position with insertion or records as has been previously described. 50

Thus, it will be seen that I have provided a completely automatic recording device which will, upon the energization of a main switch, cut a record, play back the record, deliver the record to the customer, and then stop in readiness for a 55 new cycle of operation.

I claim:

1. An automatic recording and playback machine comprising a motor energized by a main control switch, a turntable driven by said motor, 60 means for placing an uncut record over said turntable, means for raising said turntable to engage and rotate said record, a cutter, means for lowering said cutter onto said rotating record, means for traversing said cutter across said 65 record at a constant relatively slow rate, means for lifting said cutter from said record after a defined length of track is cut thereon, means for returning said cutter to initial position at a relatively rapid rate, and means for visually indicating the beginning and end of cutting. 70

2. An automatic recording and playback machine comprising a motor energized by a main control switch, a turntable driven by said motor, means for raising said turntable to engage and 75

control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier to said cutter when cutting, and second switch means for connecting said transducer as a loud speaker to the output of said amplifier and said reproducer to the input of said amplifier when reproducing.

10. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier to said cutter when cutting, second switch means for connecting said transducer as a loud speaker to the output of said amplifier and said reproducer to the input of said amplifier when reproducing, and means for de-energizing said motor after said record has been moved away from said turntable.

11. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier to said cutter when cutting, second switch means for connecting said transducer as a loud speaker to the output of said amplifier and said reproducer to the input of said amplifier when reproducing, means for storing energy over a portion of cycle of operation, and means for utilizing said energy to disconnect the main switch at a predetermined point in the recited cycle.

12. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier and simultaneously connecting the output of said amplifier to said cutter when cutting, second switch means for connecting said transducer as a loud speaker to the output of said amplifier and said reproducer to the input of said amplifier when reproducing, means for visually indicating the beginning and end of cutting, and means for de-energizing said motor after said record has been moved away from said turntable.

13. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier to said cutter when cutting, second switch means for connecting said transducer as a loud speaker to the output of said amplifier and said reproducer to the input of said amplifier when reproducing, means for visually indicating the amount of cutting time as consumed, and means for de-energizing said motor after said record has been moved off said turntable.

14. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, a record carrier, a vertical stack of records in said carrier, a slide horizontally movable beneath said stack and over said turntable, lug means on said slide for simultaneously pushing a cut record off said turntable and depositing the bottom record.

in said stack over said turntable, means for moving said slide, a transducer, switch means for connecting said transducer as a microphone to the input of said amplifier and simultaneously connecting the output of said amplifier to said cutter during cutting, second switch means for connecting said transducer as a loud speaker to the output of said amplifier and said reproducer to the input of said amplifier when reproducing, and means for de-energizing said motor after a cut record has been moved off said turntable.

15. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, a record carrier, a vertical stack of records in said carrier, a slide horizontally movable beneath said stack and over said turntable, lug means on said slide for simultaneously pushing a cut record off said turntable and depositing the bottom record in said stack over said turntable, means for moving said slide, a transducer, switch means for connecting said transducer as a loud speaker to the output of said amplifier and said reproducer to the input of said amplifier when repro-

ducing, means for storing energy over a portion of cycle of operation, and means for utilizing said energy to disconnect the main switch at a predetermined point in said cycle.

16. An automatic recording and playback machine comprising a motor energized by a main control switch, an amplifier energized by said switch, a turntable driven by said motor, means for placing an uncut record over said turntable, means for raising said turntable to engage and rotate said record, a cutter, means for lowering said cutter onto said rotating record, means for lifting said cutter from said record after a defined length of track is cut thereon, means for returning said cutter to initial position, means for lowering a reproducer onto the beginning of said cut track, means for raising said reproducer off said record at the end of said cut track, means operating after reproduction to move said cut record off from said turntable, a transducer, switch means for connecting said transducer as a microphone to the input of said amplifier and simultaneously connecting the output of said amplifier to said cutter when cutting, second switch means for connecting said transducer as a loud speaker to the output of said amplifier and said reproducer to the input of said amplifier when reproducing, means for visually indicating the beginning and end of cutting, means for stacking a supply of records, means for feeding a single record at a time from said stack to a position over said turntable, and means for de-energizing said motor after said record has been moved off said turntable.

JESSE J. WARNER. 35
